(57) **CLAIM**

(**) Term: **14 Years**

The ornamental design of an acoustic rack door for a computer server system, as shown and described.

(21) Appl. No.: **29/253,064**

DESCRIPTION

(22) Filed: **Feb. 1, 2006**

FIG. 1 is a front, right perspective view of the acoustic rack door;

(51) **LOC (8) Cl.** **14-02**

FIG. 2 is a front, left perspective view of the acoustic rack door;

(52) **U.S. Cl.** **D14/446**

FIG. 3 is a front view of the acoustic rack door;

(58) **Field of Classification Search** D14/441-446,

FIG. 4 is a top view of the acoustic rack door;

D14/308; D13/162, 184, 199; 312/223.2,
312/326; 361/680-686, 690-696, 727; 369/14,
369/34.01, 36.01

FIG. 5 is a right side view of the acoustic rack door; and,
FIG. 6 is a left side view of the acoustic rack door.

See application file for complete search history.

The bottom view of the acoustic rack door is identical to FIG. 4.

(56) **References Cited**

The back view of the acoustic rack door is unornamented.
The broken lines are shown in the views for illustrative
purposes only and form no part of the claimed design.
